ADJUSTABLE CAM FOLLOWER

Loren R. Barker, Peoria Heights, Dwight W. Parken, Washington, and Donald C. Kaiser, Peoria, Ill., assignors to Caterpillar Tractor Co., Peoria, Ill., a corporation of California

Filed Apr. 22, 1960, Ser. No. 24,071

5 Claims. (Cl. 123—90)

This invention relates to cam followers of the kind employed in an internal combustion engine such for example as those used between cams and valve stems where the cams are employed to open the valves against the force of springs which close them.

The clearance between the cams and followers is critical in an internal combustion engine if smooth, efficient and relatively quiet operation is to be obtained.

It is the object of the present invention to provide means contained within a cam follower to vary clearance or adjust the effective length of the follower by simple turning movement which may be accomplished with a conventional tool.

A further object of the invention is to provide means in such cam follower to preserve the clearance for which it is set by preventing accidental turning movement as the result of vibrations set up by engine operation.

Further and more specific objects and advantages of the invention are made apparent in the following specification wherein it is described in detail by reference to the accompanying drawings.

The invention is disclosed herein as adapted to an engine having one or more overhead cam shafts with cams arranged in alignment with the axes of the valves though its adaptability to other environments will become apparent upon an understanding of its construction and operation.

In the drawings:

FIG. 1 is a sectional view through a portion of the cylinder head of an internal combustion engine showing a cam follower embodying the present invention in place therein between the cam and valve stem with which it is associated, the section being taken on line I—I of FIG. 2;

FIG. 2 is a sectional view looking upwardly on the line II—II of FIG. 1;

FIG. 3 is a fragmentary detail showing a modification of one part of the cam follower illustrated in FIG. 1; and

FIG. 4 is a similar view illustrating another modification thereof.

Referring first to FIG. 1 of the drawings a portion of an engine head block is shown at 10 as being bored for the sliding reception of an inverted cup-shaped cam follower 11 which engages a spring seat 12 secured to the upper end of a valve stem shown at 13. A cam shaft 14 disposed above the cam follower has a cam with a lobe 15 thereon which, upon rotation of the shaft, will engage the cam follower and depress it to open the valve at the opposite end of the stem 13 against the force of the spring 16 which normally holds the valve closed.

The structure so far described is, of course, duplicated for each valve in the engine, the number of valves depending upon the number of cylinders in the engine as well as the number of valves employed per cylinder. The cam shaft 14 is rotated in a well-known manner by being geared to the crankshaft of the engine and the valves are the usual intake and exhaust valves which control communication with the combustion chamber of the engine.

In the cam follower of the present invention, contact between the follower and the spring seat at the end of

2

the valve stem is made through a threaded post 18 disposed centrally of the interior of the follower so that upon rotation it will be advanced toward or away from the valve stem. The threaded post 18 is provided with

5 an annular flange with a serrated edge 20 disposed just above the upper surface of the spring seat 12 and the seat 12 has an annular concentric groove for the reception of the end of a Phillips screwdriver as shown in broken lines at 23. The Phillips screwdriver is insertable through an angularly disposed bore 24 in the side wall of the cam follower which guides the screwdriver to a position where its fluted end meshes with the serrations 20 when its extreme end rests in the groove 22. Consequently when the screwdriver is turned, its fluted

10 end acts in the manner of a gear meshing with the serrations 20 to impart rotation to the post 18 and effects adjustment of the clearance between the top of the cam follower and the base circle of the cam. A proper clearance is established by a feeler gauge as represented in

15 dotted lines at 26 inserted between the cam and the top of the follower. Thus, simply turning the screwdriver, which is positively guided to its proper position with relation to the parts with which it is used, effects adjustment of the effective length of the cam follower.

20 25 To prevent unintentional turning of the threaded post 18 which might occur due to vibrations set up by operation of the engine, a plug 27 of nylon, Derlin or other similar relatively soft material is pressed against the threaded periphery of the post 18 as by means of a set

20 30 screw 28. This set screw may be of the countersunk or Allen head-type which can be advanced to press the plug 27 against the post 18 after the cam follower has been adjusted. To prevent loss of the set screw due to engine vibration, or even backing out of the screw to

35 a position where it would interfere with reciprocation of the follower, the bore in which it is received is only partially tapped leaving a shoulder 29 adjacent its outer end. Tapping is accomplished from the opposite side of the cam follower through a bore shown at 30 in

40 dotted lines, and the set screw and plug are also inserted through this bore.

A modification of the means just described for preventing accidental rotation of the post 18 is shown in FIG. 3 wherein the plug 27 is urged against the post

45 45 by a spring 32 held in place as by a welsh plug 33. A still further modification is shown in FIG. 4 wherein the same plug 27 and the spring 32 are contained in a blind hole which is drilled from the opposite side of the head through the opening 30 shown in FIGS. 1 and 2.

50 We claim:

1. A cam follower of the kind described comprising a reciprocable cup-like member with an open end embracing a valve stem which has a spring seat adjacent its end, a closed end engageable by the lobe of a rotatable cam, a post threaded in the follower concentric and engageable with the valve stem, a flange on said post, and means to facilitate engagement of said flange for rotating said post to vary the effective length of the follower.

60 2. A cam follower of the kind described comprising a reciprocable cup-like member with an open end embracing a valve stem which has a spring seat adjacent its end, a closed end engageable by the lobe of a rotatable cam, a post threaded in the follower concentric and engageable with the valve stem, a flange on said post, said flange having a serrated edge, and said follower having an opening to guide a tool with a fluted end portion into engagement with the serrated edge whereby rotation of the tool will rotate the post to vary the effective length of the follower.

65 70 3. A cam follower of the kind described comprising a reciprocable cup-like member with an open end em-

bracing a valve stem which has a spring seat adjacent its end, a closed end engageable by the lobe of a rotatable cam, a post threaded in the follower concentric and engageable with the valve stem, a flange on said post, said flange having a serrated edge, and said follower having an opening to guide a tool with a fluted end portion into engagement with the serrated edge whereby rotation of the tool will rotate the post to vary the effective length of the follower, said flange being disposed adjacent to and concentric with the spring seat, and said spring seat having an annular groove to receive the end of said tool while it is operatively engaged with said serrated edge.

4. A cam follower of the kind described comprising a reciprocable cup-like member with an open end embracing a valve stem which has a spring seat adjacent its end, a closed end engageable by the lobe of a rotatable cam, a post threaded in the follower concentric and engageable with the valve stem, a flange on said post, means to facilitate engagement of said flange for rotating said post to vary the effective length of the follower, and means frictionally engaging said post to prevent accidental rotation thereof.

5. A cam follower of the kind described comprising a reciprocable cup-like member with an open end em- 15

bracing a valve stem which has a spring seat adjacent its end, a closed end engageable by the lobe of a rotatable cam, a post threaded in the follower concentric and engageable with the valve stem, a flange on said post, 5 means to facilitate engagement of said flange for rotating said post to vary the effective length of the follower, and means frictionally engaging said post to prevent accidental rotation thereof, said last means comprising a plug of soft material engaging the threads on the post 10 and means to urge it into firm engagement with the threads.
